UNITED STATES PATENT OFFICE.

LOUIS B. PRAHAR, OF BROOKLYN, NEW YORK.

DESIGN FOR A BACK FOR BRUSHES OR SIMILAR ARTICLES.

SPECIFICATION forming part of Design No. 35,609, dated January 28, 1902.

Application filed December 4, 1901. Serial No. 84,711. Term of patent 14 years.

To all whom it may concern:

Be it known that I, LOUIS B. PRAHAR, a citizen of the United States, and a resident of the city of New York, borough of Brooklyn, in the county of Kings and State of New York, have invented and produced a new and original Design for the Backs of Brushes or Similar Articles, of which the following is a full, clear, and exact description, reference being had to the accompanying drawing, forming a part thereof, wherein is shown a plan view of the back of a toilet article embodying the features of my design.

The leading feature of the design consists in the peculiar shape or outline of the back, wherein the outer end marginal line *a* is convexed or arched and the side marginal lines *a'* are continuations of the end portions of the end marginal line *a*, the said side marginal lines *a'* converging to a marked extent

at their inner ends and meeting at said ends the side lines *b* of a handle *B*.

The minor features of the design consist in an ornamentation *c* at the marginal portion of the back and the apparent division *d* between the handle and the back. 25

Having thus described my invention, I claim as new and desire to secure by Letters Patent—

The design for the back of a brush or similar article, substantially as shown and described. 30

In testimony whereof I have signed my name to this specification in the presence of two subscribing witnesses.

LOUIS B. PRAHAR.

Witnesses:

J. FRED. ACKER,
JNO. M. RITTER.
